CLAIM

The ornamental design for an articulated figure knee joint, as shown and described.

DESCRIPTION

FIG. 1 is a perspective view of the articulated figure knee joint;

FIG. 2 is a side elevation view of the articulated figure knee joint, the opposite side being identical;

FIG. 3 is a posterior elevation view of the articulated figure knee joint; and,

FIG. 4 is an anterior elevation view of the articulated figure knee joint.

The broken line drawing of an articulated figure is included for the purpose of environmental structure only and forms no part of the claimed design.

The dotted lines which define the boundaries of the claimed design form no part thereof.
